UNITED STATES PATENT OFFICE

WILLIAM L. SCRIBNER, OF CANTON, OHIO, ASSIGNOR TO THE TIMKEN ROLLER BEARING COMPANY, OF CANTON, OHIO, A CORPORATION OF OHIO

CAR-JOURNAL CONSTRUCTION

Application filed March 19, 1927. Serial No. 176,629.

My invention relates to roller bearing constructions for railway car axles and the like and has for its principal object a car journal construction that is easy to assemble and dis-
5 mantle, that is capable of carrying heavy radial and thrust loads and that permits relative movement as between the car body and the axle.

The invention consists principally in
10 mounting a slideable seat member or box in the main journal box, providing said seat with a portion that is curved lengthwise of the axle and curving the outer bearing member of the roller bearing to cooperate there-
15 with. The invention further consists in the car journal construction and in the parts and combinations and arrangements of parts hereinafter described and claimed.

In the accompanying drawing, which
20 forms part of this specification and wherein like reference characters indicate like parts wherever they occur,

Fig. 1 is a longitudinal sectional view of one end of a railway car axle embodying my
25 invention, the construction of the other end being the same but with the parts in reverse position; and

Fig. 2 is an end view, with one half of the construction shown in section.
30 Each end portion 1 of a railway car axle 2 is reduced in diameter and a sleeve 3 on each end of the axle is seated against the shoulder formed at the inner end of said reduced portion 1. Seated against said sleeve 3 is the large end of the cone or inner bearing member 4 of a conical roller bearing. A spacing ring 5 is mounted on the axle against the small end of said cone 4 and the small end of a second bearing cone 6 is disposed against
35 said spacing ring. A locking and adjusting nut 7 is threaded onto the end of the axle to hold said bearing cones in position.

Conical bearing rollers 8 are mounted on each cone, preferably being provided with
45 suitable retaining cages 9, and a common cup or outer bearing member 10 is provided for the two sets of bearing rollers. Said cup is convexly curved lengthwise of the axle to fit a curved seat formed on the inner surface of
50 a box or seat member 11 of substantially semi-

circular section. Said box member 11 is disposed in the housing or main journal box 12. Movement of the axle endwise toward the outer end of the journal box is limited by an internal rib 13 extending part way around the inner periphery of the journal box. Said inner box 11 has projecting lugs 14 at its ends that engage the ends of said rib 13, thus preventing the inner box 11 from turning in the outer journal box 12.

A closure ring 15 is secured to the inner end of each journal box and has a projecting tubular flanged portion 16 encircling the sleeve 3 on the axle. Said sleeve 3 may have an up-
60 standing annular rib 17 disposed in a larger annular recess 18 in the closure ring 15. Said closure ring 15 may be provided with transverse passageways 19 opening into said annular recess 18 and into the interior of the journal box; whereby any lubricant escaping from the journal box along said sleeve 3 will, by centrifugal force, be thrown back into the journal box.

A cap 20 is provided for the outer end of the journal box 12. Said cap 20 may be provided with a removable plug 21; and a removable plug 22 may be provided in the bottom of the outer journal box. The outside of the journal box is of any suitable or stand-
65 ard construction to cooperate with the side frame and equalizer of a railway car.

The above described car journal construc-
70 tion permits relative movement as between the car axle and journal box, accommodates canting of the bearings without causing them to jam, and provides lubrication for the mem-
75 bers that permit movement and self-alignment of the parts. The inner box member has lugs on both sides, so that it is reversible. The use of a spacing ring between the bearing cones permits accurate positioning of the bearings; since they can be properly located and then a spacing collar of the precise size required introduced. Bearings removed from the journal box can be replaced without change or the spacing collar may be reduced in size to compensate for any wear of the bearings. The outer journal box may be easily slipped off endwise, after loosening the closure ring, making it easy to inspect the
80

90
95
100

bearings. The entire bearing assembly may be easily removed. Obviously, numerous changes may be made without departing from the invention and I do not wish to be limited to the precise construction shown.

5 What I claim is:

10 1. A car journal construction comprising a journal box, an axle extending thereinto, a seat member slidably mounted in said journal

15 box and provided with a seat on its inner surface that is curved lengthwise of the axle, a bearing cup having its outer surface curved to fit said seat, a bearing cone mounted on said axle and bearing rollers interposed between said cup and said cone, said journal box being provided with an internal rib and said inner box having end lugs engaging the ends of said rib to prevent rotation of said inner box.

20 2. A car journal construction comprising an axle, a pair of conical roller bearings therefor, said roller bearings having a common outer bearing member that is convexly curved lengthwise of said axle, an arcuate seat member having a concavely curved seat portion to fit said outer bearing member, and a journal box in which said seat member is mounted.

25 3. A car journal construction comprising an axle, a pair of conical roller bearings therefor, said roller bearings having a common outer bearing member that is convexly curved lengthwise of said axle, an arcuate seat member having a concavely curved seat portion to fit said outer bearing member, and a journal box in which said seat member is mounted, said journal box being provided with an internal rib and said seat member having end lugs engaging the ends of said rib to prevent rotation of said seat member in said journal box.

30 4. A car journal construction comprising an axle, having a reduced end portion, bearing cones thereon, a spacing ring between said bearing cones, a nut on said axle to hold said cones in place, rollers on said cones, a common outer bearing member for said rollers that is convexly curved lengthwise of said axle, an arcuate seat member having a concavely curved seat portion to fit said outer bearing member, and a journal box in which said seat member is mounted, said journal box being provided with an internal rib and said seat member having end lugs engaging the ends of said rib to prevent rotation of said seat member in said journal box.

35 5. A car journal construction comprising an axle having a reduced end portion, bearing cones thereon, a spacing ring between said bearing cones, a sleeve on said reduced portion of said axle against which one of said bearing cones abuts, a nut at the end of said axle to hold said cones in place, rollers on said cones, a common outer bearing member for said rollers that is convexly curved

lengthwise of said axle, an arcuate seat member having a concavely curved seat portion to fit said outer bearing member, and a journal box in which said seat member is mounted, said journal box being provided with an internal rib and said seat member having end lugs engaging the ends of said rib to prevent rotation of said seat member in said journal box.

40 6. A car journal construction comprising an axle, a pair of conical roller bearings on each end thereof, said roller bearings at each end having a common outer bearing member that is convexly curved lengthwise of said axle, a seat member for each outer bearing member having a concavely curved seat portion to fit said outer bearing member, a journal box at each end of the axle in each of which one of said seat members is mounted, each of said journal boxes being provided with an internal rib near its outer end and said seat members having end lugs engaging the ends of said ribs whereby rotation of said seat members in said journal boxes is prevented and endwise movement of said axle in said journal boxes is limited.

45 7. A car journal construction comprising an axle, a journal box therefor, roller bearings interposed between said axle and said journal box, a sleeve on said axle having an annular rib at the end, a closure ring in the end of said journal box having a tubular portion encircling said sleeve and having an annular recess into which said sleeve rib projects and said closure ring also having transverse passageways communicating with said recess and with the interior of said journal box.

50 Signed at Canton, Ohio, this 11th day of March, 1927.

55 WILLIAM L. SCRIBNER.
